[57] CLAIM

The ornamental design for a dispensing system, as shown and described.

DESCRIPTION

FIG. 1 is a left side view of the dispensing system of the present invention;

FIG. 2 is a right side view of the dispensing system of FIG. 1;

FIG. 3 is a rear view of the dispensing system of FIG. 1;
FIG. 4 is a front view of the dispensing system of FIG. 1;
FIG. 5 is a top view of the dispensing system of FIG. 1; and,
FIG. 6 is a bottom view of the dispensing system of FIG. 1.
The central protruding portion in FIGS. 1-4 is broken away to show indeterminate length.
